UNITED STATES PATENT OFFICE.

HARRY LEE CONSTABLE, OF BRIGHTON, ENGLAND, ASSIGNOR OF ONE-HALF
TO PERCY HULBURD, OF LONDON, ENGLAND.

BRAKE MECHANISM FOR RAILWAY-CARRIAGES OR SIMILAR VEHICLES.

SPECIFICATION forming part of Letters Patent No. 599,524, dated February 22, 1898.

Application filed May 17, 1897. Serial No. 636,941. (No model.)

To all whom it may concern:

Be it known that I, HARRY LEE CONSTABLE, a subject of the Queen of Great Britain, residing at Brighton, in the county of Sussex, 5 England, have invented new and useful Improvements in or Connected with Brake Mechanism for Railway-Carriages or Similar Vehicles, of which the following is a specification.

10 This invention relates to a novel construction of parts for facilitating the fixing in position or removal of the brake-blocks of continuous and other railway-brakes.

Hitherto the brake-blocks have usually been 15 attached by means of nuts or other devices held in position by cotters and split pins. By the use of this invention all such devices which require the use of tools for applying or removing them are done away with, my invention 20 proved construction admitting of removing a brake-block and replacing it without the use of any tools, while at the same time the block is securely held.

According to my invention the brake-block 25 is suspended from a pendulous link, which is inserted through a horizontal passage in the back of the brake-block into a vertical recess therein. The end of the brake-beam enters a transverse aperture or hole, with which the 30 said vertical recess and horizontal passage communicate, but is too large to pass through or into the said recesses, whereby when the end of the said beam is in position in the block the link is prevented from entering the horizontal passage of the block, so that the 35 said block cannot become inadvertently detached from the pendulous link. On the end of the brake-beam is a gravity-catch which when the brake-beam is being inserted into 40 the transverse aperture is placed horizontally, so that it will pass through the horizontal passage, and which when the brake beam and block are in their proper relative positions drops to prevent the said block and beam from 45 becoming disconnected.

In some cases I find it advantageous to make the end of the brake-beam of square or other suitable shape to prevent the block from assuming an inclined or tilted position 50 relatively with the said beam, which might

cause it to rub against the wheel when the brake is not on.

To enable my invention to be fully understood, I will describe the same by reference to the accompanying drawings, in which—

55

Figure 1 is a side elevation illustrating the construction of and mode of applying a brake-block according to my invention, and Fig. 2 is a rear view of the same. Fig. 3 is a view of a modified form of pendulous link which 60 may be employed; and Fig. 4 is a view similar to Fig. 1, illustrating a slight modification of my invention.

Similar letters of reference indicate corresponding parts in the several figures.

65

a is the brake-block, which has formed in it a transverse aperture or hole *b*, adapted to receive the end of the brake-beam *c*—that is to say, the beam through the medium of which the pressure is applied to the block 70 and which carries a brake-block at each of its ends.

d is the vertical link-receiving recess which extends from the hole *b*, and *e* is the horizontal passage which communicates with the said 75 hole *b*.

f is the pendulous link which is suspended from the frame of the carriage or the like and which supports the brake-block, the lower bar *g* of the link being introduced through 80 the passage *e* into the vertical recess *d* before the end of the brake-beam is passed into the hole *b*. It will be obvious that when the link has been thus applied to the brake-block and the end of the beam *c* introduced into 85 the hole *b* the block *a* cannot become detached from the said link *f*.

h is the gravity-catch, which swings freely on a pin on the end of the beam *c*. When this catch is held in the horizontal position 90 indicated by the dotted lines in Fig. 1, it will be obvious that the brake-block can be moved laterally to put it on or take it off the end of the beam *c*, but when the catch drops by gravity it will prevent the said block from 95 becoming detached from the end of the beam.

To prevent the brake-block from swinging forward and bearing against the wheel at its upper end, as it might do in practice, I form upon the said block a projection *i*, which 100

comes into contact with the pendulous link *f* and retains the block in its proper position.

To permit of reversing the blocks when they become worn and to avoid the necessity 5 for making right and left blocks, I provide a vertical recess *d'* below the hole *b*, corresponding with the vertical recess *d*, as clearly shown in Fig. 1, and I also provide a duplicate stop *i'* for maintaining the position of 10 the block when the link is in the slot *d'*.

In order that when applying the block to the pendulous link the stop *i* can pass through the link, I make the said link of gradually-increasing width from the bottom to the top, 15 as shown in Fig. 2, so that if when applying the block to the link the bar *g* is placed in the vertical recess *d'* the projection *i* will be opposite to a sufficiently wide part of the link *f* to pass through it, whereby when the block 20 is dropped so that the bar *g* is in the recess *d* the said lug *i* will be opposite a narrower part of the link *f*, as shown in Fig. 2; or instead of making the link of gradually-increasing width it may be formed, as shown in 25 Fig. 3, with parallel sides having two notches or recesses *j j*, which will pass over the lugs *i i*.

If the end of the brake-beam *c* is made square and introduced into a square hole *b*, as shown in Fig. 4, instead of into a round 30 hole, as shown in Fig. 1, the lugs *i i'* may be dispensed with, as the brake-beam *c* not being capable of turning and the blocks not being capable of turning upon the beam it will be obvious that the said blocks cannot tip 35 forward to bring one end into contact with the wheels.

Having now particularly described and ascertained the nature of my said invention and in what manner the same is to be performed, 40 I declare that what I claim is—

1. The combination with the brake-beam, of a brake-block provided with a transverse aperture therethrough, to receive the brake-beam, and having the portion of the block in 45 rear of said aperture cut away to form an open passage, of less vertical width than the brake-beam, extending from the said transverse aperture to the rear face of the block, and a movable retaining device on said brake-beam 50 adapted to pass through said open passage, substantially as described.

2. The combination with the brake-beam and a gravity-catch secured thereto, of a brake-block provided with a transverse aper-

ture therethrough, to receive said beam, and 55 having the portion of the block in rear of said aperture cut away to form an open passage of less diameter than the brake-beam, extending from said transverse aperture to the rear face of the block and adapted to permit the passage of the gravity-catch when the latter is in a horizontal position, substantially as described. 60

3. The combination with the brake-beam, of a brake-block provided with a transverse aperture therethrough, a link-receiving recess above and a link-receiving recess below said aperture, communicating therewith, the said block in rear of said transverse aperture being cut away to form a passage extending 70 from said transverse aperture to the rear wall of the block, and a movable retaining device on said brake-beam adapted to pass through said passage, whereby said block can be reversed, substantially as described. 75

4. The combination with the brake-beam provided with a gravity-catch at its outer end, of the brake-block provided with a horizontal slot to receive said beam and a vertical recess communicating therewith and a link engaging said vertical recess, said block being provided with means for maintaining it in vertical position with respect to said link and beam, substantially as described. 80

5. The combination with the brake-beam 85 provided with the gravity-catch, of a brake-block provided with a horizontal slot to engage said beam, a vertical recess above and below said slot, to receive a supporting-link and projecting lugs adjacent to its upper and 90 lower ends to engage said link to keep the block in vertical position, and the link provided with widened portions to permit the passage of the said lugs therethrough, substantially as described. 95

6. The combination of a brake-block having a hole such as *b* and slots such as *d*, *e* formed therein and communicating with the said hole of a link from which the said block is suspended, a brake-beam the end of which 100 prevents the block from becoming detached from the link and a gravity-catch pivoted upon the end of the said brake-beam, substantially as described.

HARRY LEE CONSTABLE.
